UNITED STATES PATENT OFFICE.

EDUARD THÜREY, OF DEUTZ, GERMANY.

TYPE-WRITING MACHINE.

SPECIFICATION forming part of Letters Patent No. 741,739, dated October 20, 1903.

Application filed December 17, 1901. Serial No. 86,221. (No model.)

To all whom it may concern:

Be it known that I, EDUARD THÜREY, a citizen of the free city of Hamburg, residing at Deutz, near Cologne, Prussia, German Empire, have invented new and useful Improvements in Type-Writing Machines, of which the following is a specification.

In type-writers with a type-cylinder as hitherto employed the type-cylinder is adjusted to bring it into position for impressing the various letters or signs by being turned on its axis in one direction or the other, two actuating-arms operated by key-levers being employed, one arm for effecting the rotation in one direction and the other arm for effecting rotation in the other direction. In this construction if both arms are to be alternately set in motion it is necessary that the working parts take a position of repose, so that one of the said arms shall not make any disturbing movement while the other of the said arms is in motion. This might, for instance, occur if accidentally two key-levers for effecting rotation of the type-cylinder in opposite directions were simultaneously operated or if a key were struck before the previously-operated key had returned to its position of rest. For this reason it is apparent that while the one actuating-arm is in motion the other should be arrested. For arresting the type-cylinder in the zero position and for preventing a simultaneous actuation of the same by two arms I according to my invention arrange upon the axis of the type-cylinder a disk provided with a stop which in the zero position of the cylinder is between the two arms, the said disk being also provided with a ring having an opening on each side of the said stop. Each of the actuating-arms is provided with a toothed segment to act on a pinion on the axis of the type-cylinder and also with an extension or pin, which extensions or pins in the position of rest of the type-cylinder are situated, respectively, on either side of the aforesaid stop and opposite the opening of the ring.

The invention is illustrated in the accompanying drawings, in which—

Figure 1 is a side view, and Fig. 2 a plan, while Fig. 3 shows a modified construction. a and a'' are the actuating-arms; b , a pinion

mounted upon the type-cylinder axis c , on which act the toothed segments z and z'' on the ends of the actuating-arms. Upon the type-cylinder axis c is fixed a disk M , consisting of the ring or flange r and the stop n . On both sides of this stop an opening or passage m is provided in the ring for the pins s' and s'' , provided on the actuating-arms.

The mode of operation of this device is as follows: In the zero position of the type-cylinder any movement thereof is prevented by the stop n of the disk M bearing against the projections or pins s', s'' of the two arms a', a'' . When one of the arms—for instance, the right-hand one—is moved, it liberates the stop, the extension or pin s'' of the arm enters the opening m of the ring, and the segment z'' acts on the pinion b so as to turn the disk and the type-cylinder. During the movement of the type-cylinder the other arm, a' , is locked by the ring r on the disk M as the extension or pin s' of that arm a' bears against the periphery of the said ring, and the said arm can only be moved when the type-cylinder and the said disk are returned to their position of rest, in which the opening m of the ring r is again opposite the extensions or pins of the arms.

In the hereinbefore-described construction, Figs. 1 and 2, the actuating-arms are arranged vertically to the axis of the type-cylinder, while in Fig. 3 the device is shown as adapted to a type-cylinder type-writer having its plane of operation parallel to the axis of the type-cylinder.

What I claim, and desire to secure by Letters Patent of the United States, is—

1. In a device for adjusting the type-cylinder of a type-writer, the combination with the type-cylinder shaft and a pinion mounted to rotate therewith, of two actuating members carrying oppositely-arranged racks for engaging the pinion to rotate the type-cylinder in opposite directions, a stop and an annular flange mounted to rotate with the pinion, and projections on said members for engaging said stop to lock the type-cylinder in its normal position and for engaging said flange to lock one of said members during the actuating movement of the other of said members, said flange being formed to leave an opening

on each side of said stop to permit said members to make their actuating movements, substantially as described.

2. In a device for adjusting the type-cylinder of a type-writer, the combination with the type-cylinder shaft and a pinion mounted to rotate therewith, of two actuating members carrying oppositely-arranged racks for engaging the pinion to rotate the type-cylinder in opposite directions, a stop and an annular flange mounted to rotate with the pinion, and means moving with said members for engaging said stop to lock the type-cylinder in its normal position and for engaging said flange

to lock one of said members during the actuating movement of the other of said members, said flange being formed to leave an opening on each side of said stop to permit said members to make their actuating movements, substantially as described.

In testimony whereof I have hereunto set my hand in presence of two subscribing witnesses.

EDUARD THÜREY.
